UNITED STATES PATENT OFFICE.

JOSEPH E. WORMALD AND ORVILLE W. AMES, OF SPOKANE, WASHINGTON,
ASSIGNORS OF ONE-THIRD TO JOSEPH S. FRYE, OF SAME PLACE.

ACETYLENE-GAS GENERATOR.

SPECIFICATION forming part of Letters Patent No. 657,150, dated September 4, 1900.

Application filed January 8, 1900. Serial No. 746. (No model.)

To all whom it may concern:

Be it known that we, JOSEPH E. WORMALD and ORVILLE W. AMES, citizens of the United States, residing at Spokane, in the county of 5 Spokane and State of Washington, have invented a new and useful Acetylene-Gas Generator, of which the following is a specification.

Our invention relates to an improved gas-generator, one object of our invention being to provide an automatically-controlled acetylene-gas generator that feeds calcium carbide to water in quantities varying with the consumption of the gas, thereby preventing an 10 undue or insufficient pressure of the gas from existing at any time while the gas is being consumed, and hence avoiding danger of exploding, while maintaining the gas at a pressure sufficient to produce lights of maximum 15 candle-power at all times.

A further object of our invention is to provide an acetylene-gas generator which is cheap, of simple construction, and which requires but little attention when in operation. 20

To these ends our invention consists in the peculiar construction and combination of elements hereinafter fully set forth, and pointed out in the claims.

In the accompanying drawings, Figure 1 is 25 a vertical sectional view of an acetylene-gas-generating apparatus embodying our improvements. Fig. 2 is a detail vertical sectional view at right angles to Fig. 1 on the line *x* *x* of that figure. Fig. 3 is a detail view 30 of the cog rack and wheel and connections for operating the automatically-controlled carbide-feeding device. Fig. 4 is a detail horizontal sectional view taken on the line *a* *a* of Fig. 3. Fig. 5 is a detail vertical sectional 35 view of a portion of the lower cylindrical section of the gas-generating tank, showing the construction of the washing-chamber and the water-feed pipe therefor. Fig. 6 is a detail perspective view showing a portion of the cog-rack and the pivoted counterweighted 40 guide-bar therefor.

The gas-generating tank 1 comprises the upper cylindrical section 2 and the lower cylindrical section 3. At the base of the cylindrical section 3 is a washing-chamber 4, adapted to hold water, through which the gas 45

passes after being generated for the purpose of purifying the gas. To the upper end of the section 3 and surrounding the same is secured a ring-plate 5, which is provided with 55 a series of peripheral recesses 6. A similar ring-plate 7 is secured to the lower end of the upper section 2 of the gas-generating tank and bears upon said ring-plate 5, a suitable packing 8 being introduced between said 60 ring-plates, and said ring-plates being secured together by means of T-bolts 9 in the opening 6 and thumb-nuts 10 on said T-bolts. Said ring-plates are hinged together on one side, as at 11, and hence by removing the T- 65 bolts the upper section of the gas-generating tank may be turned on its hinge and swung over from above the lower section of said tank to enable access to be obtained to the interior of said lower section of the tank. 70

A generating-box or cylindrical receptacle 12 is placed in the lower section of the gas-generating tank and is adapted to be removed therefrom at pleasure, and this receptacle 12 is charged with a suitable quantity of water 75 with which to generate acetylene gas from the carbide, which is introduced into said chamber. A gas-pipe 13 communicates at its upper end with the upper portion of the lower section of the gas-generating tank, and the 80 lower portion of said gas-pipe 13 passes into and extends through the water-chamber 4 and is provided with a series of perforations 14, through which the gas escapes into the water in said chamber. The latter is supplied 85 with a vertical pipe 15, which communicates at its lower end with the bottom of said water-chamber and is provided at its upper end with a funnel-shaped enlargement 16. The height of this pipe 15 is considerably in excess of that of the water-chamber, and its function is not only to enable the water-chamber to be supplied with water, but to maintain a column of water outside said water-chamber which column of water, while 90 preventing the escape of gas from the water-chamber at normal pressure, will permit the escape of gas at abnormal pressure, and hence serve as a device for preventing undue accumulation of gas and consequent explosion. 100 A stop-cock 17 is provided for the water-chamber, by means of which the water may be

drained when it becomes necessary to cleanse said water-chamber.

On one side of the lower section of the gas-generating tank is secured a chamber 18, having a false top and bottom 19 and 20, respectively, of foraminous material, and in which chamber wool or other suitable substance is packed, as at 21, said chamber being provided with an opening 22 at one side for the introduction and removal of the wool, which opening is normally covered by a glass which permits the contents of the chamber to be seen and the condition thereof to be ascertained. A pipe 23 connects the water or gas-purifying chamber 4 with the lower end of the chamber 18 at a point below the foraminous false bottom thereof, and a discharge gas-pipe 24 leads from the upper end of said chamber 18 and is provided with a stop-cock 25.

20 A cock or faucet 26 is provided for the lower portion of the lower section 3 of the gas-generating chamber for the purpose of draining the chamber of any water which may get into said tank and to facilitate the cleansing of said tank.

25 In the upper section 2 of the gas-generating tank is secured a funnel-shaped shell 27, which forms the bottom of the carbid tank or hopper 28 and which is provided at its lower side, where its walls converge, with a feed-port 29. In the top of the tank-section 2 is an opening 30, through which the carbid in a pulverized condition is placed in the feed-hopper, the said opening having a glass closure 31, which permits the inspection of the contents of the hopper. A pressure-equalizing pipe or passage 32 communicates with the lower portion of the upper tank-section 2, as at 33, and with the upper portion of the carbid-receptacle, as at 34, the function of this pipe or passage being to admit acetylene gas to the upper portion of the feed-hopper and equalize the pressure on the carbid, and thereby counteract the tendency of the gas to force 40 the pulverized carbid upwardly from the feed-port of the hopper.

45 A horizontally-movable feed-slide 35 operates in a suitable guideway 36 below the discharge-port of the carbid tank or hopper, the said slide being provided with a discharge opening or port 37, which is adapted to register with the discharge-port 29 and to open the same to any required extent, according to the quantity of carbid to be fed to the gas-generator. A worm 38 is secured on and is adapted to rotate with the feed-shaft 39, which has its bearings in the side of the carbid-tank at a distance above the port 29, as at 40, and the said shaft is also provided 50 with a bearing 41 in one side of the tank-section 2, which bearing is provided with a packing-gland 42 to prevent the escape of gas from said bearing. To the projecting end of the shaft 39 is keyed a spur or cog wheel 43. 55 On that portion of the feed-shaft which is within the walls of the carbid tank or hopper are radial stirring-spurs 44, which rotate

with the shaft in the carbid at the bottom of the hopper and serve to stir and agitate the mass of pulverized carbid at that point and insure its being fed to the port 29. A feed-worm 45 is keyed to said feed-shaft above the discharge-port and is provided with peripheral projections or spurs 46, the function of which is to feed the pulverized carbid to the discharge-port as the worm rotates. The worm 38 engages a groove 47, formed between a pair of lugs 48 on the outer end of the slide-valve, and hence as said worm rotates the said slide will be moved, as will be readily understood.

Near the gas-generating tank is located a gas-holder 49, which comprises the usual water-tank 50 and the bell or gasometer 51, the lower portion of which is submerged in 85 the water contained in the water-tank and which is adapted to rise and fall, according to the quantity of gas and the pressure thereof in said bell or gasometer.

Extending through the center of the water-tank 50, from the bottom of a base-chamber 52 under said water-tank to a point at a suitable height above the top thereof, is a guide-pipe 53, which is open at its upper end and from near the lower end of which extends a safety or pressure discharge-pipe 54, which communicates with the outer air at a suitable point. A pipe 55 connects the pressure discharge-pipe 54 with the gas-pipe 13 between the gas-generator and the purifying-chamber, and in the said pipe 55 is a cock or valve 56, adapted to establish communication between said pipe 13 and the pressure or discharge pipe 54. A pressure discharge and guide pipe 57 is arranged vertically in 100 the center of the bell or gasometer and depends from the top thereof to a point slightly above the lower edge of said bell or gasometer, the said pipe 57 telescoping on the pipe 53. The diameter of the pipe 57 exceeds 105 that of the pipe 53 considerably, and said pipes are provided on their contiguous sides with projecting guide-lugs 58, which serve to center the pipe 57 on the pipe 53 and to maintain the same at all times in a vertical 110 position thereon, and hence also to center the bell or gasometer in the water-tank and to permit only vertical motion to the said bell or gasometer. It will be observed by reference to Fig. 1 that when the bell or gasometer is 115 at the upper normal limit of its vertical motion the lower end of the pipe 57 is submerged a slight distance, and thereby a wall or water column 59 is always normally maintained in the lower portion of said pipe.

120 Within one side of the water-tank 50 is a vertical guide-rod 60, which extends through a guide-lug 61 on the proximate side of the bell or gasometer, and while permitting the latter to rise and fall in the water-tank under varying pressures of gas prevents said bell or gasometer from oscillating or rotating.

125 A gas-inlet pipe 62 is coupled to the pipe 24, as at 63, said gas-inlet pipe extending ver-

tically through the column of water in the water-tank 50 and communicating at its upper end with the interior of the bell or gasometer, as shown. A gas outlet or supply pipe 64, 5 which is of the same height as the pipe 62, is also located in the water-tank, communicates at its upper end with the interior of the bell or gasometer, and extends to the burners or other places of consumption of the acetylene gas.

A weighted box or hopper 65 is on the top of the bell or gasometer for the reception of any suitable weights which may be required to regulate the pressure of the gas in the gas-holder. In the event of an abnormal pressure of gas in the gas-holder the latter will rise high enough to withdraw the lower end of the pipe 57 from the water in the tank 50, and thereby permit the escape of the excess of 20 gas through said pipe 57 into the upper end of the pipe 53, through which it will escape to the pipe 64 and from thence into the outerair.

A cog-rack 66 has its upper end hinged, as at 67, to an arm or bracket 68, which projects 25 from one side of the bell or gasometer near the upper end of the latter. The said cog-rack engages one side of the spur-wheel 43 on the carbid-feeding shaft, and in order to keep the cog-rack normally in engagement with 30 said spur-wheel we employ a counterweighted guide-bar 69, which is pivoted to a lug or offset 70 on one side of the water-tank, as at 71, and is provided at its inner end with a U-shaped yoke 72, which bears against the plane 35 side. When it becomes necessary to disengage the cog-rack from the spur-wheel to permit the upper gas-tank section 2 to be opened, the said guide-bar may be unshipped from the said cog-rack, as will readily be understood.

The operation of our invention is as follows: As gas is consumed from the bell or gasometer the latter in descending carries the cog-rack 66 with it, and rotary motion is communicated to the carbid-shaft 39 through the spur-wheel 43, and the initial rotation of the worm 38, which engages with the slide-valve causes the latter to open the discharge-port 29 of the carbid tank or hopper, the revolving feed-worm 45 and stirring-spurs 44 serving to feed the pulverized carbid through the discharge-port into the gas-generating tank 12. If the consumption of the gas is sufficient to cause the bell or gasometer to descend with celerity, the speed of the carbid-feed mechanism will be correspondingly increased, thereby causing an increased quantity of the pulverized carbid to be fed to the generating vessel or chamber and an additional quantity of gas to be generated and discharged into said bell or gasometer in quantity sufficient to increase the pressure therein to a degree corresponding with the quantity of gas that is being consumed. In the 65 event that the gas should be generated faster than it is being consumed the bell or gasom-

eter will be caused to rise under the increased pressure of the gas therein and reverse the rotation of the feed-shaft 39 and the worm 38, hence causing the latter to move the valve 70 35 and restore the same to its initial position and cut off the discharge-port 29.

It follows from the foregoing that the operation of the carbid-feed mechanism of our improved acetylene-gas generator is automatically controlled by the pressure of gas in the bell or gasometer, and hence that the calcium carbid is fed to the water in the generating-chamber in quantities varying with the consumption of the gas, thus preventing an undue or insufficient pressure of gas from existing at any time while the gas is being consumed, whether the gas is feeding one or any number of lights, thus maintaining the gas at all times while being used at a pressure sufficient to produce lights of maximum candle-power, while effecting an economy of carbid and preventing gas from being generated when it is not being consumed.

The function of the chamber 18, in which 9c the wool is packed and through which the gas passes on its way from the water or purifying chamber 4 to the gasometer, is to dry the gas as it passes through the wool and deprive it of moisture.

The function of the pipe 55 and cock 56 therein is to permit the escape of gas from the generating-tank to the outer air before opening the said tank for the purpose of recharging or cleansing the same, and hence carrying off the odor.

Having thus described our invention, we claim—

1. The combination, in carbid-feeding mechanisms for acetylene-gas generators, of the feed-slide, the worm to actuate said slide, the gas-pressure-actuated bell, and connections between the latter and the worm, for the purpose set forth, substantially as described.

2. In carbid-feeding mechanism for acetylene-gas generators, the combination of the feed-slide, the worm to actuate the same, and the revoluble stirring devices in the throat or discharge of the hopper, substantially as described.

3. The combination, in acetylene-gas-generating apparatus, of the gas-pressure-actuated bell, the hinged rack-bar carried thereby and the yoke-bar adapted to bear against said rack-bar, with the carbid-feeding mechanism having the gear engaging said rack-bar, for the purpose set forth, substantially as described.

4. In an acetylene-gas generator, the combination of the feed-slide, the feed-shaft connected to and actuated by a gas-pressure-actuated bell, said shaft having the worm to actuate said feed-slide, and stirring devices actuated by said shaft, for the purpose set forth, substantially as described.

5. In an automatically - operated carbid-feeding mechanism for acetylene-gas genera-

tors, the combination with the gas-holder, of the feed-carbid receptacle having the port 29, the slide-valve 35, the feed-shaft 39, operated by the gas-holder, the worm 38 on said shaft, and adapted to actuate said slide, and the feed-worm 45 actuated by said shaft, substantially as described.

In testimony that we claim the foregoing as

our own we have hereto affixed our signatures in the presence of two witnesses.

JOSEPH E. WORMALD.
ORVILLE W. AMES.
